[57] **CLAIM**

The ornamental design for a body board, as shown and described.

DESCRIPTION

FIG. 1 is a top, front and right side perspective view of a body board embodying my new design;

FIG. 2 is a bottom, rear and left side perspective view thereof;

FIG. 3 is a vertical section taken generally along the line 3—3 of FIG. 1;

FIG. 4 is a right side elevational view of the body board shown in FIGS. 1-3, the left side elevational view being a mirror image thereof;

FIG. 5 is a top plan view thereof;

FIG. 6 is a front elevational view thereof;

FIG. 7 is a rear elevational view thereof; and,

FIG. 8 is a bottom plan view thereof.

FIG. 1

FIG. 2

FIG. 3
